FIG. 2

FIG. 3

FIG. 4

FIG. 5

FIG. 6

FIG. 7

FIG. 8

FIG. 1 is a perspective view of a cover plate for radiators embodying my novel design;

FIG. 2 is a top view thereof;

FIG. 3 is an elevational side view thereof;

FIGS. 4 and 5 are top views of modified forms of the cover plate of my new design;

FIG. 6 is an enlarged fragmentary plan view of the form of the invention shown in FIG. 2;

FIG. 7 is an enlarged fragmentary plan view of the form shown in FIG. 4;

FIG. 8 is an enlarged fragmentary plan view of the form shown in FIG. 5.

FIGS. 1 and 2 and 4 through 8 are broken away to indicate indeterminate length.

The essential feature of the invention resides in the depending forward portion of the cover plate which lies adjacent to the plurality of forwardly inclined vanes and extends parallel therewith.

I claim:

The ornamental design for a cover plate for radiators, substantially as shown and described.
